UNITED STATES PATENT OFFICE.

FREDERICK T. SNYDER, OF OAK PARK, ILLINOIS.

DOOR FOR ELECTRIC FURNACES.

1,100,994.

Specification of Letters Patent. Patented June 23, 1914.

Application filed October 28, 1912. Serial No. 728,089.

To all whom it may concern:

Be it known that I, FREDERICK T. SNYDER, citizen of the United States, residing at Oak Park, in the county of Cook and State of Illinois, have invented a certain new and useful Improvement in Doors for Electric Furnaces, of which the following is a full, clear, concise, and exact description.

10 My invention relates to doors for electric furnaces, and its object is to provide a door of simple construction, which will act as a plug to close the charging opening to the furnace and which can be adjusted to accurately fit such opening.

One feature of my invention consists in the construction of the door itself.

Another feature relates to the manner in which the door is mounted upon its hinges, 20 whereby the door, as it is swung open, may also be rotated about a vertical axis and may thus always be maintained in such position that the outer face of the door is turned toward the workman who opens the door.

25 My invention also provides means whereby the door may be adjusted upon its hinges so as to be brought into true alinement with the charging opening.

Still another feature relates to the structure of the hinge and to the means of mounting the same.

My invention also contemplates means for securing the door in its closed position.

These and other features of my invention 35 may be more readily understood by reference to the accompanying drawings, in which—

Figure 1 is a side elevation of an electric furnace provided with a door embodying my invention; Fig. 2 is a section on the line 40 2—2 of Fig. 1; Fig. 3 is an enlarged, fragmentary view showing the means for securing the door in its closed position. Fig. 4 is a bottom plan view of the structure shown in Fig. 3; Fig. 5 is a fragmentary, enlarged 45 detail view of one of the two similar bearings for the trunnions which form a pivotal mounting for the door; Fig. 6 is a plan view of the furnace shown in Fig. 1, two of the positions which the door may assume 50 in its open position being indicated in dotted lines upon opposite sides of the furnace; and Fig. 7 is an enlarged, vertical section of one of the two similar adjustable cone bearings of the door-hinge.

Similar letters of reference refer to similar parts throughout the several views.

The furnace 1 is provided with an inwardly tapering charge opening 2 adapted to be closed by a correspondingly tapering door 3 which acts as a plug to close said opening. Both the opening 2 and the door 3 are of circular cross-section.

The door 3 comprises an outer metallic casting or frame 4 having a peripheral flange 5 provided with an inwardly extending annular extension. Fitting the inner face of the frame 4 is a plug of fire-proof material, said plug having the form of a frustum of a cone. Said plug is made up of a number of bricks 6, such bricks tapering inwardly, as indicated in Fig. 2, and also tapering toward the longitudinal center of the door, as indicated in dotted lines in Fig. 1. Each of the bricks 6 is cut away at its inner corner, as indicated in Fig. 2, so that when said bricks are assembled the inner end of the assembled brick-work of the door has formed therein a central cavity 7. Said bricks are held in their assembled relation by a T-bolt 8, which extends through a clamping plate 9 in the bottom of the cavity 7. The end of the bolt 8 extends through the frame 4 and is fitted with a nut 9. After the bricks are clamped in their assembled relation, the cavity 7 is filled with fire clay 10.

The door 3 is pivoted to rotate upon its hinge 11, such rotation being on a vertical axis. To thus pivot the door the frame 4 is provided with diametrically opposite trunnions 12, journaled in bearings 13, carried by the upper and lower arms 14, 14^a of the hinge 11. The bearings 13 are in the form of eccentric socket-pieces which are clamped to the arm 14, 14^a by means of the U-shaped bolts 15. By adjusting the eccentrics 13 the central, vertical axis of the door can be adjusted either inwardly, outwardly or laterally, or, more broadly speaking, in any horizontal direction, and thus the door, after being properly adjusted vertically, in the manner presently to be described, can be brought into exact alinement with the opening 2.

The hinge 11 comprises the vertical post 11 and the two horizontal arms 14, 14^a. Mounted near the upper and the lower portions of the furnace are brackets 16, 16, in which are threaded the pins 17, 17. Said

pins fit in sockets in the opposite ends of the post 11 and provide a pivot bearing. By adjusting the pins 17, 17 in their respective brackets, the hinge 11 can be adjusted vertically to bring the door 3 into proper alignment with the charging opening.

Pivoted upon the end of the arm 14 by a bolt 19 is a latch 18 which is adapted to be swung by its operating handle 20 beneath a hook 21 and thus to secure the door in its closed position. It is obvious that by means of washers 22 about the bolt 19 the latch 18 can be so adjusted inwardly or outwardly as to accurately fit beneath the hook 21 and hold the door tightly closed.

Surrounding the charge opening 2 is self sustaining circular arch ring 22 of refractory brick. By having the door of circular cross-section, I am enabled to make this door arch circular and thus particularly adapted to resist lateral pressure from all directions tending to close up the door opening, especially pressure due to the expansion of the furnace lining by great heat. The arch 22 tapers toward the center, thus providing a large opening at the outside for moving the handles of rabbles and other furnace tools and a small opening at the inside, where the movement of the tools is less. This form of opening reduces to a minimum the radiation of heat through the opening. These plug doors are mounted on diametrically opposite sides of the furnace, so that the common axis of the doors will pass through the axis of the electrode 25. By opening both doors, this arrangement of the doors permits the white-hot electrode being viewed from one door against the dark outside background visible through the other door. Both doors are placed at equal distances from the furnace spout 24 to enable the condition of the inner furnace lining at each side of the spout to be observed from the opposite door.

It is important, in the operation of electric furnaces, that the furnace door closely fit the charging opening, not only to prevent the escape of the heat from the furnace, but to close the furnace against access of the outside air, since otherwise an oxidizing atmosphere may be produced in the furnace injurious in its effect upon the charge being smelted. My invention is designed, therefore, to provide a door which acts as a close-fitting plug. Moreover the brickwork of the door being subjected to intense heat will, when the door is thrown open, radiate heat to such an extent that it is desirable to protect the workmen therefrom. For this reason the door is so mounted upon its trunnions 12, 12 that, while it is being swung open, it can also be turned around into either of the positions indicated in dotted lines in Fig. 6, in which latter positions the intensely hot fire brick plug

is turned away from a workman when he has occasion to open the furnace door.

In furnace doors as heretofore commonly constructed, namely to slide up and down, it has been necessary to have counterweights to balance the weight of the doors so as to permit of easy movement. With my type of pivoted door, no counterweight is required. In a tilting furnace with sliding doors, inconvenience is caused by the swing of the door-counterweights when the furnace is tilted. With my type of hinge mounting the hinges can be mounted on the side of the door which will be above when the furnace is tilted, so that the doors will swing shut automatically when the furnace begins to tilt and thus protect the workmen tapping the furnace from the escape of heat from the door openings.

I claim:—

1. The combination with a furnace having an inwardly tapering door opening, of a tapering refractory plug adapted to enter and close said opening, and a hinge for said plug providing means for moving said plug into and out of said door opening and also for rotating said door upon an axis independent of the axis of the hinge.

2. In a furnace door, the combination of a plug of refractory material, an outer frame to which said plug is secured, a hinge comprising a pivoted post having two arms, and means for pivoting said frame between said arms.

3. In a furnace door, the combination of a plug of refractory material, a hinge comprising a pivoted post having two arms extending therefrom, and pivots for rotatably mounting said plug between said arms.

4. In a furnace door, the combination of a plug of refractory material, a hinge comprising a pivoted post, and means for pivoting said plug to said hinge upon an axis substantially parallel to the axis of rotation of said post.

5. The combination with a furnace having a conical door opening, of a conical refractory plug adapted to enter and close said opening, and means for hinging said plug to move in and out of said door opening and also to rotate on a vertical axis.

6. In a furnace door, the combination of a plug of refractory material, a hinge-member comprising a post having two arms extending from near the opposite ends thereof, means for pivoting said post at its opposite ends, said means being adjustable to adjust said hinge-member, and means for adjustably pivoting said plug between said arms.

7. A furnace door comprising a circular outer frame; a tapering plug having the shape of a frustum of a cone, said plug being formed of interchangeable bricks of refractory material and each of said bricks

- being cut away to provide a central cavity in said plug; a clamping plate in the bottom of said cavity; and a clamping bolt extending through said clamping plate and 5 said outer frame.
8. In a furnace door, the combination of a plug of refractory material, an outer frame to which said plug is secured, a hinge comprising a vertical, pivoted post having 10 an upper and a lower arm, and means for pivoting said frame to said arms.
9. In a furnace door, the combination of a plug of refractory material, an outer frame to which said plug is secured, a hinge 15 comprising a vertical, pivoted post having an upper and a lower arm, vertical trunnions extending from said frame, socket-pieces having eccentric sockets therein constituting bearings for said trunnions, and 20 means for adjustably securing said socket-pieces to said arms.
10. In a furnace door, the combination of a plug of refractory material, a hinge-member comprising a vertical post having an upper and a lower arm, means for pivoting 25 said post at its opposite ends, said means being adjustable to vertically adjust said hinge-member, and means for adjustably pivoting said plug between said arms.
11. In a furnace door, the combination of a plug of refractory material, a vertically pivoted hinge-member comprising a vertical post having an upper and a lower arm, means for pivoting said plug between said 30 arms, a latch pivoted upon the outer end of
- one of said arms, and a hook beneath which said latch is adapted to engage to lock said door in its closed position.
12. In a furnace door, the combination with a plug of refractory material, of a hinge 40 comprising a vertical, pivoted post having an upper and a lower arm, and pivots for rotatably mounting said plug between said arms.
13. The combination with a furnace and 45 means for tilting the same, said furnace being provided with a door opening and a pouring spout, of a door hinged at that side of the door opening farthest removed from said spout, whereby said door tends to 50 close by gravity when the furnace is tilted forwardly.
14. The combination with an electric furnace having a pouring spout and an electrode located in the vertical plane through 55 the axis of said spout, of doors on opposite sides of said furnace, said doors having a common axis and being so spaced from said spout that the common axis of said doors passes through the axis of said electrode 60 perpendicularly to the vertical plane through the axis of said spout.

In witness whereof, I hereunto subscribe my name this 26th day of October, A. D., 1912.

FREDERICK T. SNYDER.
